UNITED STATES PATENT OFFICE.

EMANUEL EINSTEIN, OF NEW YORK, N. Y.

DESIGN FOR NAP-SURFACE OF CLOTH.

SPECIFICATION forming part of Design No. 12,632, dated December 27, 1881.

Application filed October 13, 1881. Term of patent 7 years.

To all whom it may concern:

Be it known that I, EMANUEL EINSTEIN, of New York city, county and State of New York, have originated a novel Design for the 5 Nap-Surface of Cloth, of which the following, in connection with the annexed drawing, is a full, clear, and exact description.

This design is more especially intended to be produced by being cut into the nap of the cloth 10 in the act of shearing the same, such as those designs patented to me June 7, 1881; but it might also be produced by weaving, although not to such advantage.

The figure in the annexed drawing presents 15 a perspective view of a piece of cloth finished according to my design.

The essential feature of my design consists in the series of parallel serpentine or undulating lines or grooves *a a*, laid diagonally across 20 the cloth, for while it has been common heretofore to arrange straight lines diagonally and serpentine lines lengthwise of the cloth, yet serpentine lines have never been arranged diagonally, which produces a novel effect, which 25 distinguishes my present design.

This design may be produced on or in the cloth in any suitable manner, either by weaving or otherwise; but I prefer to employ it more particularly for heavy or beaver cloths, such 30 as are finished with a surface nap or pile, and to cut the design into the surface nap or pile in the act of shearing the same, as this gives a more novel and striking effect distinct from the more common diagonals or worsteds. In 35 this case, as shown in the drawing, the general wearing or napped surface of the cloth is presumed to be finished or sheared smooth or uniform, like a smooth or rough faced beaver-cloth, while a figured effect is produced upon 40 this uniform napped surface according to my design by cutting the diagonal serpentine

grooves *a a* therein. These grooves are preferably placed at such a distance apart as to leave comparatively wide bands *b* of the uniform nap between them, which bands have, of course, an undulating form similar to the grooves, and necessarily parallel with them. The relative width of the grooves and the bands may, of course, vary without departing from the general effect; but the proportions 45 illustrated, where the bands are much wider than the grooves, is thought much preferable. These undulating diagonal grooves *a a*, in combination with the intervening similarly-shaped bands *b b*, of smooth or level nap, form another 50 feature of my present design, for in this case the contrast of the sinuous diagonal bands of smooth or level nap with the sharply-cut grooves intervening with the same produces a very distinct appearance and forms a characteristic minor element of this design. 55

Referring now to the drawing, it may be readily noted that the optical effect of this design is such as to give the cloth the appearance of being gathered into soft and easy folds, 60 running at the opposite inclination to the grooves.

What I claim is—

1. The specified design for the nap-surface of cloth, consisting of a parallel series of sinuous or serpentine lines laid diagonally across the cloth, substantially as herein illustrated. 70
2. The design for the nap-surface of cloth, consisting of sinuous diagonal grooves, in combination with similarly-formed intervening bands of uniform or level nap, substantially as herein described, and illustrated. 75

EMANUEL EINSTEIN.
